COMPRESSED AIR DEEP WELL PUMP

James E. Lacy, Los Angeles, Calif., assignor of
one-half to Richard H. Lacy, San Marino,
Calif.

Application September 30, 1936, Serial No. 103,338

7 Claims. (Cl. 103—46)

My invention relates to a deep well pump such as a pump suitable for pumping oil from bored wells or for pumping water or water with minerals in solution from considerable depths below the surface of the earth.

An object and feature of my invention is to use compressed air as the motive force for pumping the oil or other liquid and in which the pump assembly is located at the desired depth in the well for receiving the oil or other liquid, which liquid is positively elevated by a plunger pump, the plunger being operated by an air engine having a cylinder and a piston. An advantage of my construction is that the only moving parts are the piston of the air motor and the plunger of the oil pump together with the actuation of the control valves. Hence there are no long reciprocating parts such as the sucker rods in the ordinary pumps leading down into the well. Another general object and feature of my invention is pumping the oil or other liquid from deep wells in stages. That is, the lowermost pump is located at the bottom of the well which pumps and thus positively elevates the oil to a higher elevation where it flows into a sealed-off chamber in the well in which the next higher pump is located, the oil being pumped upwardly through a string of oil pipe. Thus by having a succession of pumps, each of which is operated by compressed air, the oil may be elevated by stages from the bottom to the top of the well. A further feature of my invention resides in using separate air conduits or pipes connecting from the top of the well and an air compressor plant to the individual pumps. Thus by using a proper timing arrangement the pumps can be operated in a sequence, hence as only a comparatively small amount of compressed air is required for any one pump, it is not necessary to have a very large or expensive compressor plant, although of course it is desirable to use the air at high pressure in the individual pumps.

Another object and feature of my invention is in arranging the pumps and their construction suitable for use in a well in which the casing tapers in stages from the top to the bottom of the well, being smallest at the bottom. Hence as it is desirable to have as large a diameter oil pipe as possible, the lowermost pump may have the pump plunger and the piston of the air motor or engine substantially the full diameter of the oil pipe or tube. In this case the cylinder in which the piston operates for the air engine also functions as a cylinder for use in pumping the oil. In fact, the piston may function both

as the piston for the compressed air engine and as the plunger for the oil pump.

Another detail feature of my invention is in controlling the air valves by a cam which positively rotates the valves a sufficient amount to open the air valve for admitting air to the air engine on the power stroke and giving a reverse motion for exhaust. The cam for operating the rotary valve is preferably actuated by a reciprocating cross-head having a cam mounted thereon, which cross-head is positively depressed by the weight of oil above the pump. To effect this operation a small duct communicates with the oil in the oil tubing above the pump and leads to a small diameter but elongated cylinder having a piston with a connecting rod therein, the rod operating the cross-head. Another feature of my invention relates to a construction of the air engine by providing a plurality of comparatively small air valves connected with the compressed air line through the medium of a manifold. By this construction comparatively small air valves can be utilized to admit and exhaust sufficient air to lift a heavy load of oil or other liquid.

My invention is illustrated in connection with the accompanying drawings, in which:

Fig. 1 is a vertical section through a well casing with the pump assemblies in elevation. In actual practice, however, each pump assembly may be much longer in its relation to its diameter and the diameter of the casing and the oil pipe.

Fig. 2 is a vertical section taken on the line 2—2 of Fig. 8 of a form of pump suitable for a small diameter well casing. In this instance the pump barrel is the same or substantially the same diameter as the oil pipe through which the oil is pumped upwardly.

Fig. 3 is a vertical section taken substantially on the section lines 3—3 of Figs. 4, 5, and 6 showing a construction of pump suitable for the upper stages in pumping where the well casing is of larger diameter and the pump barrel of greater diameter than the oil pipe.

Fig. 4 is a horizontal section on the line 4—4 of Fig. 3 looking upwardly in the direction of the arrows.

Fig. 5 is a horizontal section on the line 5—5 of Fig. 3 looking downwardly in the direction of the arrows.

Fig. 6 is a horizontal section on the line 6—6 of Fig. 3 looking downwardly in the direction of the arrows.

Fig. 7 is a horizontal section on the line 7—7

of Fig. 3 looking downwardly in the direction of the arrows, this figure being on a smaller scale than Figs. 4, 5, and 6.

Fig. 8 is a horizontal section on the line 8—8 of Fig. 2 looking downwardly in the direction of the arrows on the same scale as Fig. 2.

Fig. 9 is a detail perspective partly broken away of one of the air control valves.

Referring first to Fig. 1, the oil well casing indicated by the numeral 11 has a lower section 12 with the perforations 13 for the inflow of oil or other liquid, this being at the bottom of the well and is usually of much smaller diameter than for instance, an upper section 14. Therefore when pumping is done in stages it is usually impractical to have a large diameter pump at the bottom of a well. The lowermost pump is indicated by the numeral 15 and is shown in detail in Figs. 2 and 8, using however the valve construction of Fig. 9. An upper or larger diameter pump is indicated by the numeral 16 and illustrated particularly in Figs. 3 through 7 having the valve of Fig. 9.

The upper type of pump is constructed substantially as follows, having reference particularly to Figs. 3 through 7 and 9. An outer cylinder or case 20 encloses the cylindrical motor barrel 21 which barrel has a lower head 22 and an upper head 23, preferably connected thereto by a threaded connection. The motor plunger or piston 24 is slidably mounted in the barrel and has a central rod 25 which extends downwardly through a guide opening 26 in the lower head 22. A piston rod 27 also connected to the plunger 24 extends upwardly through a guide opening 28 in the upper head 23. To this upper head is connected an oil pump cylinder 29 having the oil pumping piston 30 mounted on the upper end of the piston rod and working in this cylinder. The upper or small diameter string of oil pipe 31 connects to the oil pump cylinder 29 and extends upwardly in the well.

The lower end of the cylindrical case 20 is provided with an end head 35 with a guide opening 36 for the rod 25 and perforations 35'. This is preferably screw threaded into the lower end of the cylinder. This cylinder 20 terminates at the bottom in a reduction head 37 having a flange 38 to which the lower string of oil tubing 39 is connected, this leading upwardly from the lower pump 15. Thus there is an oil chamber 40 provided below the head 35 and having oil flow openings 41. An annular packer 42 of any suitable type seals off the lower portion of the pump 16 with the well casing, the packer being below the openings or perforations 41 to allow upflow of oil into an upper annular oil chamber 43 between the cylindrical case 20 of the pump 16 and the well casing.

A series of small oil reaction cylinders 50, these being shown as three in number as indicated in Fig. 6, extend downwardly in the annular space 51 between the casing cylinder 20 and the motor barrel 21. These preferably have a snug fit and by means of welded fillets 52 properly center and retain the motor cylinder mounted in a concentric and fixed position in reference to the cylinder case 20. In each of these small pipes or cylinders there is mounted a piston 53 with a downwardly extending piston rod 54, this being connected to a cross-head 55. The cross head is shown in Figs. 4 and 5 as a series of radial arms 56 leading from a central hub 57 through which hub the rod 25 passes, the hub being rigidly secured to the rod. The cross-head is shown as having three

long arms secured to the rods 54. A circular oil manifold 58 is located above the upper head 23 and supplied by oil by a small bore oil pipe 59 extending upwardly along the oil cylinder 29 and being connected as indicated at 60 to the upper part of the cylinder 29 above the flap check valve 61, this being pivoted at 62. A radial oil lead pipe 63 extends from the manifold to the upper end of each of the small bore pipes 50 (note Figs. 3 and 7). The inlet for oil to the oil pump is through the inlet elbow pipe 64 (note Fig. 3), this having a check valve 65 therein, such valve being operative for inflow of oil from the oil chamber 43 surrounding the pump to the oil cylinder 29 but preventing outflow on the up stroke. The small oil vent 66 is provided in the head 23 for inflow and ejection of oil above the plunger 24 during the reciprocating motion of this plunger under the action of compressed air.

The air supply and control assembly designated by the numeral 75 includes a plurality of individual air valves 76, three of these being illustrated, the details being presented in Figs. 3, 4, 5 and 9. Each valve has a cylindrical valve casing 77 extending downwardly from the lower head 22 which head has an inlet port 78 and an outlet port 79, these being arranged concentric with the axis of the rotary cylindrical valve plug 80. Such plug has right angular inlet air passage 81 and a longitudinal outlet air passage 82 (note particularly Figs. 3 and 9), the inlet passage being of larger diameter than the outlet passage. Air is supplied through a circular air manifold 83 located below the head 22 and connected to openings 84 through the valve casing 77. A vertical air compressed pipe 85 has a connection to the manifold 83 and passes upwardly in the annular space 51 between the cylindrical case 20 and the motor barrel 21, this having an upward lead 86 with couplings 87 following upwardly on the oil pipe string to the top of the well where such pipe is connected to a suitable air compressor or a controlled storage tank of compressed air.

The actuating mechanism for the valves designated by the assembly numeral 80 employs tubes 91, each connected at its upper end to a valve plug 80, the outlet passage 82 discharging downwardly through the pipe 91. Each pipe has a reduced journal end 92 connected to its lower end, this having a bearing 93 in the head 35 adjacent the lower end of the cylindrical case 20, there being a central air discharge perforation 94 through the head 35 and the journal end 92. The pipe 91 is provided with an upper radially projecting pin 95 and a lower radially projecting pin 96, these being at 90 degrees to each other. The cross head carries three cams, each indicated by the numeral 100 and secured to the cross head hub 57 by short arms 101 (note Figs. 3, 4 and 5). Each of these cams has an upwardly sloping face 102 and a lower sloping face 103 so that on the upward movement of the cross-head 55 when the pump plunger 24 moves up, the face 102 engages the upper pin 95 and causes a rotation of the valve plug in one direction. Likewise when the cross-head moves downwardly due to its rigid attachment to the rod 25 and the lower face 103 engages the pin 96, the tube 91 and the valve plug 80 is rotated in the opposite direction.

It will be apparent that instead of having the cylindrical case 20 and the motor barrel 21 formed as two separate elements with an annular space 51 therebetween, these can be made integral with longitudinal bores forming a provision

for the small reaction cylinders 50 and for the compressed air duct 85, as it is not really essential that there be an annular space such as 51. Also, in some cases where there is sufficient diameter 5 in the well casing to have relatively large valves, one air valve may be utilized instead of a plurality of smaller valves. Also in some cases instead of having the reaction pistons 53 to effect 10 the positive downward movement of the cross-head and hence of the cams 100, the weight of the plunger 24 or weights attached to the rod 25 may be sufficient for this purpose. It will be noted that the small pistons 53 are always subject 15 to the hydraulic head due to the weight of oil or other liquid above the flap valve 61 to the upper end of the particular length of oil pipe 31.

The manner of operation and functioning of the pump assembly designated as 16 and illustrated particularly in Figs. 3 to 7 and 9, is substantially as follows: Presuming the plunger 24 is at the bottom of its stroke adjacent the lower head 22 of the motor barrel, then the cross head 55 is at the lower part of its stroke and the lower face 103 of the cam 100 engages the pin 96 of the tube 91, thus rotating and positioning the valve plug 80 to align the inlet passage 81 with the air openings 84 to the manifold to allow compressed air to enter through the inlet port 78 in the head 22, this compressed air as above mentioned, being fed downwardly through the air pipe 86 and 85 and the manifold 83. As the piston rod 27 is carried downwardly by the plunger 24, the oil piston 30 is likewise lowered causing an inflow of oil from the annular space between the 35 well casing and the pump through the inlet 64 having the check valve 65. In this action, the downflow of oil retained in the upper part of the cylinder and the oil pipe 31 is prevented by the flap valve 61. The compressed air below the 40 plunger 24 gives an upward stroke to its plunger, which it will be noted, is of very much larger area than the oil piston 30. This creates a lift of the oil in the oil pump cylinder 29 closing the check valve 65 and opening the flap valve 61 for 45 upflow of oil in the oil pipe 31. At the same time the rod 25 carries the cross head 55 upwardly elevating the cams 100 and also by means of the rods 54, thrusting the small pistons 53 upwardly. 50 Any oil which has entered through the vent 66 above the plunger 24 in the motor barrel is expelled through this vent. When the upper sloping surface 102 of the cam 100 engages the upper pin 95 on the tube 91 it rotates the pin and the tube and hence the valve plug 80 one-quarter 55 turn, thus dis-aligning the intake passage 81 with the intake port 79 and bringing the outlet air passage 82 in the plug into alignment with the outlet port 79. This releases the air pressure in the motor barrel below the plunger 24 allowing 60 this to descend. As the small pistons 53 are always subject to the hydraulic head of the oil in the manifold 58, the small bore pipe 59 and the oil string 31, these pistons are positively forced downwardly when there is no air pressure to 65 cause their elevation. Thus even if there is a resistance to the outflow of air from below the plunger 24, the cross-head 55 positively exerts a downward pull on the rod 25 and hence on the plunger. The first action of the downward movement of the piston 30 is to cause a closing of flap valve 61, thus trapping the oil above such valve. However as above described, in certain cases the small pistons 53 with the rods 54, the oil duct 59 and the manifold 58, may be discarded. The 70 75 exhaust air as above described as passing through

the outlet passage 82 flows downwardly through the pipe 91, the discharge perforation 94, into the oil chamber 40 and hence outwardly through the oil flow openings 41 or the perforations 35 and thus mingles with the oil confined in the well casing flowing upwardly through this oil and eventually being discharged from the top of the well. It will be apparent that the motor barrel and the length of stroke provided for the cross-head 55 may be as long as desired to give a considerable lift at each stroke to a comparatively small volume of oil, the volume being regulated by the diameter of the oil cylinder 29 and the length of the stroke of the oil piston 30. In this arrangement the air is always under constant compression in the air pipes 86 and 85, supplying air to the valves, hence the rapidity of the stroke is dependent on the air pressure, the weight of the column of oil being elevated and the speed with which the plunger 24 descends.

The type of pump such as 15 for use in the lowermost part of a well where the diameter of the casing is not sufficient to accommodate the larger pump such as designated at 16, is constructed substantially as follows, having reference particularly to Figs. 2, 8 and 9. This in its main features is the same as the pump 16 above described. An elongated cylindrical case 125 has a lower perforated head 126 with perforations 127 and a central guide opening 128, which head 126 may be threaded into the lower end of this cylinder concentrically mounted in the case as a combination compressed air and oil lift cylinder 130, the lower end 131 of which is provided for the compressed air and the upper portion 131' for the oil to be lifted. A combination air plunger and oil piston 132 is mounted in the cylinder 130 and has a rod 133 extending downwardly through a guide opening 134 in the lower head 135 of the cylinder 130. This rod extends downwardly 40 through the guide opening 128. There are small bore tubes 136 forming oil cylinders located between the case 125 and cylinder 130 and having the function of the reaction cylinders 50, each being provided with a plunger 137 and a rod 138 45 extending downwardly and connected to a cross-head 139. This cross head is similar to the cross head 55 and secured to the rod 133. The cross-head is provided with cams 100 and operates the same type of valve indicated at 75 as shown in 50 connection with the pump of Fig. 3. In this case however, the tubes 140 extend downwardly from the valve plug having a perforated lower bearing 141 in the lower head 126, the exhaust air being discharged downwardly through these pipes 140. 55

It will be noted in the construction of the valve of Figs. 2 and 8 that the cylinder 130 is of the same diameter as the oil tubing 39 through which the oil is pumped upwardly. An oil inlet 142 having a check valve is provided and located below 60 the pivoted flap valve 143. A small bore oil duct 144 connects to the cylinder 130 on the oil tubing 39 above the flap valve 143 and connects to an annular manifold 145 (note (Fig. 8), this having connections 146 to each of the small oil cylinders 65 136. The compressed air is brought downwardly by a compressed air pipe 147 which leads through the annular space between the case 125 and the cylinder 130 and leads to a manifold 148 located surrounding the valve assembly 75 and supplies 70 air to these valves in the same manner as the similar manifold of the pump of Fig. 3. This air pipe 147 leads upwardly through the upper pumps 16 either through the annular space 51 or through special bores provided. By this con- 75

struction there is a separate air pipe supply to each of the pumps when these are arranged in stages.

The operation of the pump 15 considered as an individual pump is substantially the same as the pump of Fig. 3, except in this case the area of the plunger 132 on which the air operates is slightly less than the upper area lifting the column of oil. On account of this lower pump being designed for use in the lower contracted end of the well casing where the oil flows in through the perforated casing from the oil sand, it is desirable that this type of pump have a greater lift than the pump of Fig. 3.

15. The operation of an assembly of pumps for lifting the oil in stages is as follows, having reference particularly to Fig. 1: The pump 15 is operated by its own air line and lifts the oil through the lower string of oil tubing 39 which is connected as shown in Fig. 3 to the lower end of the cylindrical case 20 of the larger pump 16 next thereabove. The oil is discharged into the oil chamber 40 and flows outwardly through the ports or perforations 41 in the cylinder 20 (note Fig. 3) into the annular chamber 43 defined by the packer 42, the upper section 14 of the well casing and the cylindrical case 20, the oil being always maintained at a level well above the oil intake 64. Therefore the upper pump 16 operating on its own air system gives the oil a lift in the second stage upwardly through the string of oil pipe 31. This in its turn may be connected to a similar pump much in the same manner as the oil tubing 39 is connected to the pipe 16. Thus by having a series of pumps which may increase in size as desired as the well casing increases in diameter towards the top of the well, the oil may be pumped in succeeding stages from the bottom 40 to the top of the well for discharge in the usual manner. In order to economize on the size of the air compressor plant, this may be arranged to form a connection to the various air supply lines for the different pumps in a sequence so that one pump actuates on its lift at a time and it is not necessary to supply at one time enough air to operate all of the pumps simultaneously. It will be apparent however, if desired, that all of the pumps may be connected to the same air line, in which case it will be only necessary to run one line of air pipe from the surface to the ground to the lowermost pump, this being tapped off to the manifolds of the various pumps used in the stages above the lowermost.

55. Various changes may be made in the details of the construction without departing from the spirit or scope of the invention as defined by the appended claims.

I claim:

60. 1. In a deep well pump, the combination of an outer case structure, a combined air and liquid cylinder having a plunger therein with a rod connected to the plunger, a liquid tube connected to the upper end of the liquid cylinder 65 and having a check valve with an inlet therebelow, a valve for the air cylinder, a compressed air connection from the top of the well to the said valve, a valve operating means having a movable element connected to the said rod, with valve rotating elements operatively positioned to be engaged thereby, the valve having an inlet and an exhaust passage for air, a means to positively move the plunger downwardly comprising a small bore cylinder having 70 a small piston therein with an operative means

connecting said small piston and the rod connected to the plunger and a liquid connection from the small bore cylinder above its piston to the liquid in the liquid tube.

2. In a deep well pump in which a well bore 5 is provided with a well casing, a gas motor fitted in the casing, a liquid pump connected thereto, a gas supply pipe for the motor and a liquid pipe connecting from said pump upwardly in the well, the motor having a movable element combined with a return mechanism for the moving element of the motor having a liquid pressure connection to the liquid in the said liquid pipe to positively return the moving element of the pump to its initial position.

10. 3. In a deep well pump in which a well bore 10 is provided with a well casing, a gas motor having a reciprocating piston and a liquid pump also having a reciprocating piston, the pistons being connected, a gas supply pipe for the motor 15 leading upwardly in the well, a liquid discharge pipe from the pump extending upwardly in the well combined with a return mechanism for the piston of the pump having a liquid connection to the liquid in the liquid pipe constructed and 20 adapted to maintain a liquid pressure due to the head of liquid in the pipe with means urging the motor piston downwardly, the pressure of the gas being adapted to overcome the downward urge on the pumping stroke of the 25 motor and the pump.

4. In a deep well pump as claimed in claim 3, the liquid return mechanism including one or more small bore cylinders each with a piston 35 therein with a liquid connection from the cylinder or cylinders to the discharge liquid pipe together with means connecting the small piston or pistons to the piston of the gas motor.

5. In a deep well pump, the combination of a cylindrical case having a first cylinder for air 40 mounted concentrically therein, said cylinder having a lower head with a guide opening, the said case having a lower head with a second guide opening, a plunger mounted in the first cylinder and having a road extending through 45 the guide openings in the head of the cylinder and the lower head of the case, the lower head of the cylinder having inlet and exhaust ports, a valve having a rotary plug with inlet and exhaust passages, a compressed air connection 50 from the said valve to the top of the well, a reciprocating actuating means for the valve connected to the said road and a valve moving device connected to the valve plug to be engaged by the said actuating means to operate the said valve to align the said passage respectively with the said ports, and a liquid cylinder connected to the first cylinder having the valve, said liquid cylinder having a piston connected to the plunger, a liquid tube extending upwardly from the 55 liquid cylinder and having a check valve therein and an intake for liquid with a second check valve below the first check valve, the rod having a cross-head connected thereto, a small bore cylinder positioned between the case and the first 60 cylinder and having a small piston therein with a piston rod connected to the said cross-head, a liquid connection from the upper end of the small cylinder above its piston to the liquid tube above the check valve of said tube whereby the 65 small piston is always subject to the hydraulic head of the liquid contained in the said liquid tube for returning the cross-head and the said plunger to its lowermost position after a lifting 70 stroke.

6. In a deep well pump, an air motor cylinder having a head at the bottom with a guide opening therethrough, a plurality of air valves mounted on the lower head and having inlet and exhaust passages, an air manifold having a connection to the inlet passages, a compressed air connection from the manifold to the upper part of the well, a motor pump plunger in the cylinder having a rod extending downwardly through the guide opening in the head, a valve actuating means having a portion thereof secured to said rod to reciprocate therewith to actuate the valves simultaneously from an inlet to an exhaust position, a liquid pump having a cylinder connected to the cylinder of the air motor with a piston connected to the plunger, a liquid inlet above the piston, a check valve above the inlet and a liquid tube extending upwardly from the liquid pump cylinder, the valve actuating means including a cross-head, a plurality of small liquid cylinders connected to the air pump cylinder and each having a small piston, secondary piston rods between each small piston and cross-head, a liquid manifold connected to the upper end of each of the small cylinders, a liquid connection from said manifold to the liquid pump cylinder above the check valve of said cylinder whereby

the small pistons are always subject to the hydraulic head of the liquid in the liquid tube.

7. In a deep well pump a compressed gas motor and an oil pump connected together, the motor having a cylinder with a piston operating therein and the pump having a cylinder with a pump piston operating therein, the said pistons being connected together, an oil inlet to the oil pump above the level of the uppermost travel of the pump piston, a valve connected to the lower end of the motor cylinder, a conduit for compressed gas extending downwardly and connected to the valve, a cross-head connected to the piston of the motor, a cam on said cross-head and an interacting means between the cam and the valve to rotate the valve, such valve having an exhaust opening communicating with the well, a small bore cylinder positioned adjacent the motor cylinder having a small piston therein, an oil connection from the upper end of the cylinder to a position above a check valve of the oil pump to always maintain an oil pressure on the piston of the small cylinder and a rod connecting the small piston with a cross-head whereby the small piston and said rod always exerts a downward movement in the cross-head and hence on the motor piston.

JAMES E. LACY.
